UNITED STATES PATENT OFFICE.

JULIA WEISS, OF KENOSHA, WISCONSIN.

GARMENT.

1,349,029.

Specification of Letters Patent. Patented Aug. 10, 1920.

Application filed July 16, 1919. Serial No. 311,117.

To all whom it may concern:

Be it known that I, JULIA WEISS, a citizen of the United States, residing at 681 Fleet street, Kenosha, county of Kenosha, 5 and State of Wisconsin, have invented certain new and useful Improvements in Garments, of which the following is a specification.

This invention relates to improvements in 10 garments and has for its principal object to provide a garment adapted for use as a skirt and which may be readily converted into a pair of trousers.

Another object of the invention is to provide a garment of simple construction in 15 which the fastening means for securing certain of the parts together to form a skirt are also utilized in holding the parts together in the form of trousers.

20 With these and other objects in view, the invention consists in the novel construction, combination and arrangement of parts which will be more fully hereinafter described in the following specification, 25 claimed, and illustrated in the accompanying drawings, in which—

Figure 1 is a front view of the garment illustrating it assembled for use as a skirt. Fig. 2 is a rear view of the same,

30 Fig. 3 is a view similar to Fig. 1, showing the garment assembled for use as a pair of trousers, and,

Fig. 4 is a diagrammatic view showing 35 the connection of the various parts.

Referring to the drawing in detail, the numeral 5 designates the waist band of the garment the ends of which are secured about the waist of the wearer by buttons or other suitable fastening means 6. Secured to the waist band are the skirt sections 7 and 8 which are designed to flare 40 outward toward their lower ends to provide the desired fullness usually formed in a skirt, and secured to the sections 7 and 8 are pockets 9 as shown in Figs. 1 and 3.

The meeting edges 10 of the parts 7 and 8 at the rear of the garment are stitched or otherwise permanently secured together from a point about midway of the length 45 of the garment to the top or waist band 5, while those portions of the edges 10 between the lower end of the garment and the permanently secured portions are provided at spaced intervals with buttons and 50 button holes or other securing means 11 by

which the parts may be removably connected.

The meeting edges 12 of the parts 7 and 8 at the front of the garment are provided at spaced intervals with the buttons or 60 other fastening means 13 and are designed to open throughout the entire length of the garment.

Formed at the lower edge of each section 7 and 8 of the garment, is a relatively 65 wide hem 14 forming a tubular passage the inner wall of which is provided with a slot 15 adjacent the rear edge of its respective section through which the free end of a draw string or tape 16 passes. The opposite 70 end of the draw string or tape 16 is secured in the passage or hem 14 at the end opposite the slot 15.

Formed near the free end of the tape 16 is a buttonhole 17 and secured intermediate 75 the ends of the tape is a button 18, the use of which will be further on described.

When the garment is to be used as a skirt the same is assembled in the manner shown in Figs. 1 and 3 by connecting the 80 edges 10 and 10' and the edges 12 and 12'. The same is then worn in the usual manner.

When it is desired to convert the garment for use as trousers, the lower portions of the edges 10 are connected with the lower 85 portions of the edges 12 in the manner shown in Fig. 3 thus providing leg encircling portions.

After preparing the garment in this manner the draw-string or tape is drawn 90 tightly about the leg, so that the fullness of the parts 7 and 8 is gathered in, and the buttons 18 are passed through the button holes 17 thereby securing the tape in place.

While in the foregoing there has been 95 shown and described the preferred form of this invention it is to be understood that certain minor changes in the construction combination and arrangement of parts may be resorted to without departing from the 100 spirit and scope of the invention as claimed.

What is claimed is—

A combination garment which consists of a divided skirt secured to a suitable waist band, the upper portion of the meeting edges 105 of the skirt sections at the rear of the garment being permanently secured together, button holes and buttons on the lower portions of the meeting edges at the rear of the garment and on the meeting edges of 110

the skirt sections at the front of the garment to hold the sections in one position in the form of a skirt and in another position to form a pair of trousers, a relatively wide slotted hem at the lower edge of each section, a strap or tape provided with a button hole secured to said hem and passed through the slot thereof, and buttons inter-

mediate the ends of said tape adapted to be engaged in said button holes when it is desired to use the garment as trousers, substantially as described.

In testimony whereof I have affixed my signature.

JULIA WEISS.
